UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

TRAFFIC-SIGNAL SWITCH.

Application filed May 12, 1924. Serial No. 712,551.

This invention relates to traffic signals or signals for controlling traffic, as street traffic at street intersections and other points and has for its object a particularly simple compact switch for controlling the flow of current to the various signals or groups of signals in the system.

The invention consists in the novel features and in the combinations and constructions hereinafter set forth and claimed.

In describing this invention, reference is had to the accompanying drawings in which like characters designate corresponding parts in all the views.

Figure 1 is a plan view, partly broken away of this switch.

Figure 2 is a sectional view taken vertically and centrally on Figure 1.

Figure 3 is a plan view of the base of the switch.

Figure 4 is a sectional view taken vertically and centrally of Figure 3.

Figure 5 is a diagrammatic view of this switch and the wiring of the circuits controlled thereby.

This traffic signal switch comprises generally a base, a series of contacts mounted on the base and connected respectively to the circuits of different signals or group of signals; a switch arm movably mounted on the base and movable successively into engagement with the contacts; a cover for the base and operating means for the switch carried by the cover and detachable from the switch arm upon the removal of the cover and attachable thereto upon replacement of the cover.

1 designates the base of the switch, which is of suitable insulating material. The switch base is mounted on the base 2 of a suitable housing, it being here shown as mounted upon posts 3 rising from the bottom of the housing base 2. 4, 5 and 6 designate respectively contacts mounted in a series on the base 3; they being preferably mounted in an arc-shaped series and having arc-shaped engaging faces. 7 is the movable switch arm also mounted on the base and having a contact head 8 for engaging the contacts 4, 5 and 6 on the base. The switch arm is pivotally mounted on the base at the center of the arc of the contacts 4, 5 and 6.

The switch arm 7, as here shown, is mounted on a shaft 9 journalled in a suit-

able bearing 10 secured in the base 1, the arm having a split bearing on the shaft and being secured to the shaft by a clamping screw 11 extending through the jaws of the split bearing. The arm is usually of metal. The contact head 8 extends transversely at the outer end of the arm and is pivoted between its ends to the arm 7 and also movable radially or lengthwise of the arm 7 and is pressed by spring means toward the contacts 4, 5 and 6. The head 8, as here shown, is formed with a centrally located pivot 12 arranged in a lengthwise slot 13 in the arm and is provided with contact points, as rollers 14 at its opposite ends, these rollers being spaced apart a greater distance than the space between any two contacts 4, 5 and 6, in order to bridge the space between the contact and remain in engagement momentarily with one contact, while moving into engagement with the next contact. These rollers 14 are arranged in pairs and each pair is connected by an axle 16, which seats in a notch 17 in the end of the head 8. The head 8 is pressed toward the contacts 4, 5 and 6 by suitable means, as a spring 18, located in a recess extending lengthwise of the arm 7 and thrusting against a head 19, slideable in the recess and thrusting against the near side of the head 8 centrally thereof. Each contact 4, 5 and 6 is provided with a seat or depression 20 for receiving one of the rollers and holding the head and switch arm in its operative position when fully engaged with such contact. The spring 18 acting on the head 8 causes one of the rollers 14 to enter a seat or depression 20, spring pressed poppet fashion.

The base is inclosed by a suitable cover 21, which rests on the upper edge of the housing base 2, and is secured thereto in any suitable manner, as by screws 22, on opposite sides of the cover and threading into the base. The base 2 is provided with suitable screws 24 by means of which it may be attached by any suitable support and with an opening 25 for the wires of the circuits.

The operating means for the switch arm is carried by the cover 21 and is so connected to the switch arm that such operating means detaches from the switch arm when the cover 21 is removed and attaches to the switch arm when the cover is replaced. The operating means is movable about an axis aligned with the axis of the shaft 9 of the

switch arm. As here shown, it comprises a shaft 26 carried in a suitable bearing 27 in the cover 21 in alinement with the shaft 9, a handle lever 28 mounted on the outer end 5 of the shaft and having a handle 29 therein, and a rock arm 30 mounted on the inner end of the shaft and detachably engaged with the switch arm, it being here shown as formed with a radial slot 31 for receiving a 10 crank pin 32 on the switch arm 7. As the switch arm is of metal, an insulating cap or bushing 33 incloses the pin 23.

Also mounted on the base 1 at one side of or in the rear of the switch are switches for 15 controlling signals, such as a bell, an off-duty light and an officer's light, and, also, controlling the flow of current from the feed wires through the main switch, the latter controlling switch being a double pole switch 20 designated 34. The off-duty light and the bell are controlled by a three-way switch designated 35 and the switch for the officer's light is a single pole switch designated 36. These switches are arranged on the base 1 25 in a portion of the cover 21, which is provided with a movable cover 37. To prevent opening of the cover when the main switch is in center position, the cover is hinged at 38 to the cover portion 21, and the hand lever 30 is formed with an arm 39 which normally overhangs the free edge of the movable cover 37 and prevents opening thereof.

The switch arm 28 is provided with a lug 35 for holding it in central position, and a locking member 40 pivoted at 41 to the cover is arranged to swing upwardly to embrace the free end of the lever 28, so that, the hasp of a padlock can be passed through a perforation 42 in the free end of the lever 28 to 40 hold the lock from removal and hence hold the lever 28 from operation. This switch is particularly advantageous for controlling traffic signals and in Fig. 5 a group 43 of signals designated for controlling south 45 bound traffic, a group 44 for controlling north bound traffic, a group 45 for controlling east bound traffic and the group 46 the west bound traffic, each group usually consisting of a green, amber and red light designated respectively G, A and R, the green light indicating that the traffic is to go, the red light that the traffic is to stop, the amber light that a change is to be made from green to red or red to green.

50 47 designates a bell which operates in synchronism with the amber light, 48 designates the off-duty light, and 49 the officer's light. The officer's light is arranged above the officer to make the officer clearly visible to the traffic, and the off-duty light is to show the traffic that no officer is on duty and that, if the amber light is lit, showing that the traffic can proceed and the signal is not in operation. When the officer is off-duty, all the 55 amber lights are lit and, as the bell 47 usu-

ally operates in synchronism with the amber light, in order to avoid continual ringing of the bell when the officer is off-duty, the bell circuit is broken by the three-way switch 35, which operates to close the switch through 70 off-duty light 48 when the circuit is broken through the bell circuit.

The officer's light is controlled by the single pole switch 36 and the circuit from the feed wire to the main switch through the double 75 pole switch 34. 50 and 51 are the feed wires.

In operation, the double pole switch 34 is operated to connect the feed wires in circuit with the switch arm 7. The single pole switch 36 may be operated to close the circuit through the officer's light 49 and the three-way switch may be operated to close the circuit through the bell 47.

Now, assuming the switch arm is in central position, as shown in Figs. 3 and 5, the current passes in through a feed wire 50 to one pole of the double pole 34 through a switch conductor 52, to a pole 53 of the double pole switch, through a wire or conductor 54 to a fuse contact 55, through the fuse 56 to a fuse contact 57 through a conductor 58 binding post 59, thence through a wire or conductor 60 to the conductor 61 of the switch arm, through the head 8 and contacts 14 of the switch arm, thence through the center contact 5, wire 62 to the amber light of all groups of signals 43, 44, 45 and 46, thence through a rear wire 63 to a fuse contact 64, fuse 65, fuse terminal 66, conductor 67 to a pole 68 of the double pole switch 34, thence through a switch conductor 69 out through the main 51. Also the current flows from the central contact 5 through conductor 70, conductor 71 to a pole 72 of the three-way switch 35 through switch conductor 73 to a pole device 74 of the three-way switch 35, thence through a wire 75 of the bell circuit through the bell to return wire 63.

In case the single pole switch 36 is also operated to "on" position, the current passes from the binding post 59 through a conductor 77 to a pole 78 of the switch 36, thence through the switch conductor 79 to pole 80, thence through a conductor 81 through the lamp 49, and thence through a conductor 82 to the return wire 63.

When the switch arm 7 is actuated by turning the handle lever 28 to carry the switch arm 7 into engagement with the contact 4, the current flows through the double pole switch 34 from the wire 50, as before, through a conductor 54, fuse 56, conductor 58, binding post 59, conductor 61 of the switch arm 7 to the contact 4, thence through wires 83, and 84 to the red light of the south and north signal groups 43, 44 and to the green lights of the signal groups 45 and 46, the circuit being completed through the return wire 63, as before.

Also, when the signal is operated so that 120

it is in engagement with the contact 6, the current passes from the main 50 through the double pole switch to the fuse 56, conductor 61 of the switch arm 7 and contact head 8, as before, and from the contact 6 through wires 85 and 86 to the green lights of the signal groups 43, 44 and the red lights of the groups 45, 46, the return being made through the wire 63, as before.

10 As there is no electrical connection between the contacts 4, 6 and the three-way switch 35, the bell 47 does not ring when the switch arm is engaged with these contacts 4, 6.

15 By reason of the fact that the contact head 8 is of greater width than the spaces between the contacts 4, 5 and 5, 6, the amber lamps are energized in each case, before the red or green lamps are deenergized.

20 When the signals are to be set with the amber light, as when no officer is on duty, the officer's light switch 36 is operated to "off" position and the three-way switch 35 is operated to cut out the bell circuit and 25 cut in the circuit to the off duty light 48, so that the circuit is completed to the off duty light from the center or amber contact 5 through the conductors 70, 71, pole 86 of the three-way switch 35, conductor 87, 30 pole 88, conductor 89, through the off duty light 48 and thence through the return wires 76 and 63.

This switch mechanism, which controls a multiplicity of circuits and signals, is particularly compact in construction and consists of but few parts.

What I claim is:

1. In a switch the combination of a base, a series of contacts arranged in an arc on 40 the base and spaced apart thereon, a switch arm pivoted to the base substantially at the center of such arc, a contact head carried at the outer end of the switch arm and pivoted through and having conducting terminals on opposite sides of its axis for engaging the contact.

2. In a switch, the combination of a base, contacts arranged in an arc on the base, a switch arm pivoted to the base on an axis 50 located substantially at the center of such arc, a contact head carried at the outer end of the arm and pivoted thereto and having means on opposite sides of its pivotal axis for engaging the contacts, the head being 55 also mounted to move radially relatively to the switch arm and a spring tending to thrust the head toward the contacts.

3. In a switch, the combination of a base, a series of contacts mounted on the base, a 60 switch arm movably mounted on the base,

a switch head pivoted to the switch arm and having contacting means on opposite sides of its pivot, the switch arm being movable to carry the head successively into and out of engagement with the contacts on the base 65 and the head being of greater width than the space between the contacts, whereby the head remains in engagement with one contact while moving into engagement with the next contact and momentarily bridge the 70 space between the contacts.

4. In a switch, the combination of a base, a series of contacts mounted on the base, a switch arm movably mounted on the base, a switch head pivoted to the switch arm and 75 having contacting points on opposite sides of its pivot, the switch arm being movable to carry the head successively into and out of engagement with the contacts on the base and the contact being spaced apart a greater 80 distance than the space between the contacts, the head being mounted on the arm to move lengthwise of the arm, and a spring tending to thrust the head toward the contacts on the base. 85

5. In a switch, the combination of a base, an arc-shaped series of contacts mounted on the base, a switch arm pivotally mounted on the base concentric with the center of the arc of such contacts, a contact head pivoted to the switch arm at the outer end thereof and mounted to move lengthwise of the switch arm, the head having rolling contact points on opposite sides of its axis and the distance between the contact points being greater than the space between the contacts on the base and a spring tending to thrust the head toward the contacts. 90

6. In a switch, the combination of a base, an arc-shaped series of contacts mounted on the base, a switch arm pivotally mounted on the base concentric with the center of the arc of such contacts, a contact head pivoted to the switch arm at the outer end thereof and mounted to move lengthwise of the 100 switch arm, the head having contact points on opposite sides of the axis and the distance between the contact points being greater than the space between the contacts on the base, a spring tending to thrust the head toward the contacts, and each of the contacts on the base having a seat for receiving the rolling contact at one end of the head. 105

In testimony whereof, I have hereunto signed my name at Syracuse, in the county of Onondaga, and State of New York, this 15th day of April, 1924. 110

CARL H. BISSELL.
